US00D353530S

United States Patent [19]

Gartner

[11] Patent Number: Des. 353,530

[45] Date of Patent: ** Dec. 20, 1994

[54] ELECTRONIC KEYLESS ENTRY ASSEMBLY

4,956,984 9/1990 Chi-Cheng 70/277
4,967,577 11/1990 Gartner et al. .

[75] Inventor: Klaus W. Gartner, Palos Verdes Estates, Calif.

[73] Assignee: U-Code, Inc., Torrance, Calif.

[**] Term: 14 Years

[21] Appl. No.: 19,650

[22] Filed: Mar. 9, 1994

[52] U.S. Cl. D8/330

[58] Field of Search D8/330-331; 70/91, 101, 277, 286, 156
